UNITED STATES PATENT OFFICE.

GILBERT SELLERS, OF CHICAGO, ILLINOIS.

ELECTRICAL TRANSMISSION OF GRAPHIC MESSAGES.

939,338.

Specification of Letters Patent.

Patented Nov. 9, 1909.

Application filed July 18, 1908. Serial No. 444,227.

To all whom it may concern:

Be it known that I, GILBERT SELLERS, a citizen of the United States, and a resident of Chicago, in the county of Cook, in the State of Illinois, have invented certain new and useful Improvements in the Electrical Transmission of Graphic Messages; and I do hereby declare that the following description of my said invention, taken in connection with the accompanying sheets of drawings, forms a full, clear, and exact specification, which will enable others skilled in the art to which it appertains to make and use the same.

15 This invention has general reference to, and its object is the, improvements in the electrical transmission of graphic messages, pictures, photos, prints, &c., and visible views of fixed, living, and moving objects, 20 and to reproduce the same at the receiving station either as a graphic message or as a visible, stationary or movable picture; and it consists, essentially, in the novel and 25 peculiar combination of parts and details of construction as hereinafter first fully set forth and described and then pointed out in the claims.

This invention has its basis upon a series of physical and electrical phenomena and 30 facts the application of which, and the manner in which, they are carried into effect, may be briefly stated, as follows: According to Plateau the persistence of impression on the retina is in ordinary light one-half 35 second, such persistence depending on the intensity of the light; Newton observed a spot on the retina for days after looking at the sun. This is the cause of the streak across the retina due to a rapidly moving 40 object. (See Plateau's investigations in *Ganot's Physics* by Ganot and Atkinson.) Again according to Sale, Siemens, *International Encyclopedia*, Bell, Girard, and others, there are substances which, when in- 45 terposed into the electric circuit and exposed to various grades of light, are almost instantaneous in their resistance of the circuit or in lowering and raising the resistance relative to the light they are bathed in.

50 In the photophone and the speaking arc the wonderful control of electrical resistance is practically proved through the light cast upon crystallized selenium or on a lamp black joint. Such substances cause such 55 rapid changes to take place in the resistance

of the current as to reproduce the human voice ranging from 1,000 semi-vibrations to 40,000. *q. v.* Von Hulmholt's estimations in one second. This means as high and even higher than 20,000 changes may take place 60 in the electrical resistance of a crystallized selenium or lamp black joint in one-half second. Then if a selenium point is passed through a field of light containing 20,000 complete changes and finish its flight in one-half second, 10,000 electrical vibrations will be produced in that time in the circuit. Again, if a pencil of light pass before the retina over a field corresponding to the field over which the selenium point was passed 70 and during the same time, one will see that entire field at the latter instant of the light's passage. Then if the intensity of that light is so regulated by those 10,000 electrical vibrations, the illuminated field before the 75 eye will duplicate the field over which the selenium point was passed. These are the steps that enable me to reproduce such a scene instantaneously and so quickly that a series of scenes may be made to follow in 80 such a short succession that the sensation of movement is the result. In order to carry these principles into effect and attain the results I construct these instruments substantially as shown in the accompanying 85 sheets of drawings, which serve to fully illustrate this invention, and in which—

Figure 1 is a longitudinal, vertical section of the sending apparatus for transmitting a film image. Fig. 2 is a transverse section in line A A, and Fig. 3 a similar section in line B B of Fig. 1. Fig. 4 is a longitudinal, vertical section of the sender for transmitting an image direct from life or nature. Fig. 5 is a longitudinal, vertical section of the receiver, and Figs. 6, 7, and 8 are views of light-reflecting means in various positions. Fig. 9 is an end-view of the revolving mirrors.

1, in Fig. 1, is the sending case or receptacle having a bottom 2, sides 3, and ends 4. In the bottom 2 there is a transverse-slot 5, for the exit of a film 6. Adjacent to one of the ends 4, of the case 1, is journaled, upon a shaft 7, a film containing roller or spool 8, 100 which roller is provided with a brake band 9, to apply friction to said spool and thereby prevent undue unrolling of the film 6. In about the center of the case 1 and at the same height as shaft 7 is journaled a second 105 shaft 10, upon which is mounted a second 110

shaft 10, upon which is mounted a film-deflecting roll 11, from which roller the film 6 deflects downward and passes out of the case 1 through the slot 5. Directly above roller 11 is a feed-roller 13, impinging upon the film passing between said rollers 11 and 13. Roller 13 is fastened to a shaft 12, one end of which projects through one of the side walls 3 of the case 1, and has at its extremity a miter-gear 14; meshing with this is a similar gear 15, affixed to an upright shaft 16, which shaft is journaled in a bracket 17, fastened to the extended top 24, said extended top also serving to incase feed-roll 13. At the upper end of shaft 16 is a worm-gear 18, meshing with worm-screw 19 on shaft 20, of a motor 21, said motor being supported on the depressed top 22 of the case 1, and is energized from voltaic cells or other source of electric current 23. Motor shaft 20 extends beyond worm-screw 19, and near its outer extremity revolves in a bearing in a bracket 25, resting on the curved top 39 of the case 1. On this bracket, and encircling shaft 20 is a cylindrical shell 26, within which are located and revolve brake-shoes 27. These shoes are connected by links 28, through a slot 32, in the shaft 20, to a sliding spindle 29 in the center of said shaft. This spindle 29 terminates in a head 38, to which are connected the shanks 30 of two governor balls 40; the said shanks being pivoted at 31 to the end of the shaft 20. Within the shaft 20, and bearing against the spindle 29 is a spiral spring 33, and against this spring, butts a pin 34. Upon the shaft 20 is a screw thread 37, over which fits a threaded collar 36. Against this collar is placed a key 41 passing through a slot 35 in the shaft 20, which key pushes against the pin 34.

The office of the mechanism just described is to provide a speed-governing device for the motor for purposes hereinafter to be described. Its operation is as follows: As the motor speeds up the governor balls 40 are carried outwardly by centrifugal force, and push the spindle 29 inwardly, causing the links 28 to straighten out and the shoes 27 to finally impinge against the inner surface of the stationary shell 26. The friction so generated will retard the motor speed until it has fallen off sufficiently to allow the governor balls to drop and withdraw the shoes 27 from contact with the shell. To adjust the governor for various speeds, the collar 36 may be screwed toward or away from the slot 35, and thereby, through the intermediate of the key 41 and pin 34, create greater or lesser pressure upon the spring 33, which, in turn will establish greater or lesser resistance to movement of the spindle 29.

Mounted upon the shaft 20, at a point central, approximately, between the film rollers

8 and 11 within the case 1, is a disk 42. This disk consists of a hub 43, and two side-plates 44, spaced a proper distance apart by said hub. Near the periphery of this disk 42, and between the side-walls 44 are formed a series of equally-spaced radial cylindrical pockets 45. At the center end of these pockets, and flush with the periphery of the disk are placed condenser-lenses 48, which are so ground as to convert parallel rays of light into divergent rays within the pocket. The bottoms of these pockets 45 are closed by cups of fiber, rubber, or other insulating material 47. Within these cups are fixed circular cells of selenium 46. From these selenium cells lead wires 50 which are connected to one of the plates 44. Wires 49 also lead from the selenium, but they are thoroughly insulated from the plates 44, and are connected to commutator-sectors 51 as described below. Adjacent to the disk 42, on the shaft 20, is located a commutator 52 which is insulated from the shaft by the insulation 53. Upon the periphery of this commutator are a series of metallic sectors 51, radially arranged and insulated from each other, and corresponding in number to the number of pockets 45 within the disk 42. To each one of these sectors is connected a wire 49, mentioned above, from that one of the selenium cells located opposite each particular sector, as clearly shown in Fig. 2.

To the shaft-supporting bracket 25, already described, is attached a commutator-brush stud 55, but thoroughly insulated therefrom by insulation 57. At one end of this stud is attached a binding post 56, to which is led the current-transmission wire 60 from the receiving instrument, and at the other end is a commutator-brush 54, with its free end in contact with one of the commutator sectors 51. To the bracket 25 is fastened a binding-post 58, from which is led the current-transmission line 59 to the receiving instrument. Attention is now called to the fact that when the commutator is revolved, and the brush 54 is passing over the insulating bridge between adjacent sectors 51, the brush is in contact with both adjacent sectors for a very short period of time or space.

The top 39 of the case 1, below the disk 42 is of convex contour, its curvature being concentric to the periphery of said disk, as clearly shown in Fig. 2. Directly below the center of the disk 42, and through the top 39 is located a very narrow slot 61. The length of this slot is equal to the angle formed between the centers of two adjacent pockets 45 in the disk 42, as seen in Fig. 2. The relationship of the slot and the pockets is such that when the disk 42 is revolved, and one of the pockets is passing beyond the range of the slot, the next adjacent pocket

is just entering into range. In a similar manner, the relationship of pockets and commutator sectors is such that when one pocket is leaving the range of the slot 61, the commutator-brush is passing from the commutator-sector belonging to that pocket, to the sector belonging to the pocket just entering into range of said slot.

By reference to Fig. 1 it will be observed that the film 6, already referred to, lies in a plane directly below the top 39, and directly below said film in a perpendicular line with the slot 61, is an electric lamp 63 of a length equal to the length of the said slot. This lamp is contained in a parabolic reflector 64, which projects the rays from the lamp through the film and the slot and upon the selenium cell in that particular pocket 45 which happens to be within the range of the slot 61. Within the case 1, and on either side of the reflector 64 are two curved rollers, 62 to curve the surface of the film 6 to the curvature of the top 39 as the film is passing across the slot 61. Current for the lamp 63 is provided by the cells or other source of current 65.

Referring to the gears 14, 15, 18, and worm-screw 19, which compose the film-feeding mechanism, it will now be understood that the ratio of this gearing is such that the film is fed across the slot 61 as many times the width of the slot 61, as there are pockets in the disk 42, in one revolution of the disk; that is to say, if there are eight pockets in the disk the film must move forward eight times the width of the slot during one revolution of the said disk. Every time a pocket with its selenium cell has traversed the range of the slot, the film has moved forward the width of the slot.

The operation of this sender may now be described as follows: Assuming a live electric circuit to be established by the wires 59 and 60, the governing mechanism is adjusted to the proper speed, the lamp 63 turned on and motor 21 started. The electrical conductivity of selenium is susceptible to the action of light. Its electrical resistance is susceptible instantaneously to an infinitude of changes by said light-action. The passing of the film 6 before the slot 61, with the light projected through said film with its changes in light, and shadow, and contrasts, will affect the conductivity of the selenium within the pockets as the disk revolves rapidly before the slot, and there will be set up in the continuous current flowing through the transmission-circuit an infinitude of variations in the intensity thereof, equaling exactly the infinitude of changes in the lights, shadows and contrasts of the image on the film.

The foregoing description has reference entirely to the transmission of an image upon a film. If, however, it is desired to

transmit an image direct from life or nature, the sender illustrated in Fig. 4 is employed. The governing mechanism, the disk, pockets, selenium cells, and motor are precisely the same as in the first instance, but directly in front of the disk 42, Fig. 4, is located a ground glass 66, the sole purpose of which is to perform the functions of a range-finder. In front of this glass is a dark slide 67, having a narrow slot 85, located on a center line with the disk 42 and of a length equal to the angle formed between the centers of adjacent pockets 45 in the disks 42. The length of this slot determines the width of the image projected on the ground-glass 80 range finder.

To a frame 86, surrounding the dark slide 67 and ground glass 66, is attached a flexible camera bellows 68, terminating in a camera front 69, in which is affixed a proper photographic lens 70. This front 69 is susceptible of a perpendicular movement equal to the height of the image projected on the ground glass and is guided in its motion by the upright guides 71. These guides are stiffened at their upper ends by a brace 72 and at the bottom by the support 73.

To the edges of the camera front 69 are pivoted rods 74, which connect said front with vibrating levers 75, which levers are journaled at their opposite ends on brackets 81. On said levers 75 are rollers 80 engaging raceway cams 79. These cams are fixed to a shaft 77, which is journaled in brackets 76. Upon this shaft is keyed a worm gear 78, which meshes into worm-screw 19 on motor shaft 20. The raceway cams 79 revolve in the direction of the arrow shown thereon, and in the position shown in Fig. 4, it will be observed that only a very slight movement is necessary to permit the rollers 80 to drop down the practical radial slots 86, returning the levers 75, connecting rods 74, lens 70, camera front 69, and bellows 68 to the positions shown in dotted lines in Fig. 4. To nullify the shock due to the sudden drop of these parts spring bumpers are placed under the free ends of levers 75. These bumpers consist of external cylindrical shells 82 telescoping over smaller shells 83. Within the latter are spiral springs 84, which are in a normally extended condition. When the parts above mentioned drop, the ends of the levers 75 strike shells 82 and compress springs 84, thereby deadening the jar that would otherwise occur.

The speed of the upward movement of the lens 70 and its adjacent parts is equal to the width of the slot for every pocket 45 in the disk 42 that traverses the slot 85 in the dark slide 67. Thus if there are eight pockets around the disk 42, then the lens moves upward eight widths of the slot for each revolution of the disk. This upward movement is at a constant speed, due to the raceway in 130

the cams 79 being cut to an arc which will produce a movement upwardly of constant speed. When these cams 79 have completed one revolution, the lens has traveled upward 5 the full range of the ground-glass, and has successively presented before the slot 85 every portion of the image picked up by the lens 70. Only a slight further movement of the cam is now necessary to drop the lens 10 down again ready for another transmission. The ratio of time required to drop the lens to the time required for the upward movement is about as 1:250.

The transmission of moving images produced by the progress of a race, a pugilistic encounter, or any other life motion, is accomplished by keeping this sending apparatus in continuous motion, and as the lens completes about 250 cycles per minute, the 20 motion in life will be correctly transformed into an infinitude of current variations in the transmission circuit, through the intermediate of the selenium cells.

In Fig. 5 is illustrated the receiving mechanism, which consists of a case or receptacle 87 having a bottom 88, sides 89, top 90, and a bridge 91 for supporting the operating mechanism. Upon this bridge near one end of the case is mounted a motor 92, operated 25 by a current from a source of electricity 93. The shaft 95 of this motor has at one end a governor 94 whose construction is precisely the same as that shown in Figs. 1 and 4 and already hereinbefore described. The opposite extremity of this shaft 95 extends to the far end of the case 87 and is journaled in a bracket 115. On said shaft, adjacent to this bracket is keyed a spider 113, having a plurality of equally spaced radial arms 117, 30 each terminating in hinge-lugs 118. To these lugs, are hinged, by means of hinge ears 114 and pintles 119, Fig. 9, a plurality of mirrors 112. The opposite ends of these mirrors are connected by lugs 116 and links 35 111 to a sliding collar 110, which is adapted to freely slide to and fro on shaft 95. The number of mirrors 112 hinged to the spider 113 corresponds to the number of pockets 45 in the sending disk 42; also the circle described by the revolution of the mirrors is of the same diameter as that of the said sending disk. Furthermore, the governor 94 is set to the same speed as the governor 50 on the sending mechanism, and the size of each mirror is the same as the field of the image projected upon the ground-glass range 55 finder 66 of the said sending apparatus.

Upon the periphery of the already mentioned sliding collar 110, is turned a groove 60 109 for the reception of the forked end 108 of a vibrating lever 105. The opposite end of this lever is pivoted to a bracket 107, and intermediate of its length, is journaled a roller 106, which fits in spiral groove 120 65 of a raceway cam 104. Said raceway cam

is keyed to a shaft 102, which is suitably journaled in bearings not shown. This shaft also carries a spur gear 103, the latter meshing with intermediate gear 100, which revolves freely on a stud 101, and this in turn, meshes into worm gear 97, and the last named derives motion from the worm screw 96 on the motor shaft 95. Said worm gear 97 revolves freely on stud 98 supported in bracket 99.

Upon revolving cam 104, it will be observed, that through the action of vibrating lever 105, sliding collar 110, and links 111 the near ends of mirrors 112 will be forced radially outward until said cam 104 has made one revolution, when, because of the roller 106 passing through the practically radial portion of the groove 120, the mirrors are suddenly returned to their original position. These complete cycles are accomplished at the same speed and follow each other with the same rapidity as the cycles of the lens 70, Fig. 4. In other words, the motor 92 is synchronized with the motor 21, Figs. 1 and 4, and necessarily the movement 80 of the mirrors is in synchronism with the movement of the said lens 70, or with the movement of the film 6, Fig. 1.

Centrally above the top-most mirror 112 and of a size sufficient to permit rays of light 121 to be spread over the surface of said mirror, is cut an opening 122 in the top 90 of the case 87. Light-rays emanate from a light 123 of great intensity, which light is operated by a current from an electrical source 124. Surrounding this light is a parabolic reflector 125 and in front of the same a condensing lens 126, which focuses the rays 121 upon a small mirror 127. From there the rays are projected through a proper lens 128 and spread over the surface of mirrors 112. Adjoining the lens 128 is an absolutely opaque screen 129 for purposes hereinafter described.

The small mirror 127 is suspended by a fine quartz fiber wire or thread 130 in a high frequency disk galvanometer 131. Below this mirror is suspended a small silver disk 132 within a coil 133 consisting of a comparatively few turns of insulated wire. This coil, through its binding posts 134 and 115 135, forms part of the transmission circuit which is composed of the wires 59 and 60, the voltaic cells 136, the said galvanometer 131 and the sending apparatus. Now, the disk galvanometer 131 has the property of causing the disk 132 to oscillate about the axis of the fiber thread 130, whenever a current, no matter how feeble is passed through the circuit. The arc of the oscillation and the rapidity of successive oscillations depends entirely upon the variations and the rapidity 120 of the variations in the intensity of the current passing through the circuit. Therefore, the infinitude of variations in the current 130

as created by the selenium cells in the sending apparatus will produce an infinitude of oscillations of the disk 132, the arc of each oscillation representing the light value of that particular portion of the sending image which caused it. And the rapidity of these successive oscillations, will in the same manner correctly represent the light value of the successive portions of the image as picked up by the selenium cells. The mirror 127 being also attached to the quartz fiber 130 which suspends the disk 132, will naturally oscillate with the disk.

In order to understand the process of reproducing the image in the receiver, attention is called to Figs. 6 7 and 5. Assume the light 123 to be turned on, the motor 92 in operation, and an open circuit in the transmission line. Or, assume the lens 70 of the 15 sender to be capped. In this case the disk 132 of the galvanometer will be in a normal position, and that position is shown in Fig. 6, wherein all the light rays from lamp 123 are blanketed upon dark screen 129 and none 20 of them pass through the lens 128 to the mirrors 112. If the sender now be started and a current established in the transmission line, the disk 132 and mirror 127 will oscillate and permit a portion of the light rays 121 to pass 25 through the lens 128 and be deflected upon the mirror 112, the amount of light so passing through the lens being directly proportionate to the light value of that particular portion of the sending image at that precise 30 instant. As the light value of the image increases, the current in the line increases, and the mirror 127 twists through a greater arc, permitting a greater portion of light to pass 35 through the lens 128 and upon the mirrors 40 112. When the mirror 127 has twisted sufficiently to permit the full light from the lamp 123 to be spread upon mirrors 112, the equivalent of sunlight streaming through the lens 70 of the sending apparatus has been 45 obtained. The relative position of the mirror 127 to the mirrors 112 is such that the radial movement of the mirrors 112 from the normal to the extreme position shown in dotted lines in Fig. 5, will cause the rays 121 50 to travel from the point A on said mirrors to point B thereon. This movement corresponds to the movement of the lens 70, and as the revolution of these mirrors is synchronized to the revolution of the sending 55 disk 42, the exact conditions existing in the sending apparatus are reproduced in the receiver. The light values projected upon the mirrors 112 being relatively the same as in the sending image, the impression produced 60 upon the human eye upon looking through the opening 122 of the receiver will be that of the image transmitted. It will be further observed that the image of the message, or that of a moving object, a view, &c., received at the receiving station is exhibited 65

to the human eye through the opening 122 upon the mirrors 112 which are passing before the retina of the eye in rapid succession and overlap each other so as to appear to the eye as a moving picture if the original was 70 a moving picture, or as a stationary or fixed object, as the case may be. To throw these pictures upon a screen or upon a sensitive film, they are picked up by a projection apparatus (not shown) of usual construction 75 from the mirrors 112 and then developed in the usual manner.

In the foregoing specification I have described the preferred form and construction and instrumentalities with which my present 80 invention is carried into effect, but I desire it to be distinctly understood that the various details of the several instruments described may be varied in many ways without departing from my invention.

Having thus fully described this invention I claim as new and desire to secure to me by Letters Patent of the United States—

1. Means for electrically transmitting graphic messages and views of objects, including a message-sheet of varying degree of transparency; a source of light; means for projecting the light from said source of light through said message-sheet by a step-by-step movement; a series of rotating, 90 light-sensitive, elements upon which the rays of light are projected after passing through said message-sheet; an electrical circuit including said light-sensitive elements; means for transmitting the various 100 undulations in the intensity of the current in said circuit caused by the action of the light-rays upon the light-sensitive elements, to a receiving station, and a reproducing instrument therein including means for translating the varying undulations of said current into a visible reproduction of the transmitting message.

2. The method of electrically transmitting messages and views of objects, which 110 consists in exposing said messages, and views of objects, successively and step by step to a series of rapidly revolving light-sensitive substances which will change its electric conductivity in accordance with the intensity of the light acting upon said substances, and transmitting the electrical undulations or variations in the intensity of the current and the rapidity of the undulations to a reproducing instrument and to translate these 115 electrical undulations and varying impulses into light-rays of correspondingly varying intensity and projecting the same upon a reflecting surface which renders them visible to the human eye.

3. In an apparatus for electrically transmitting messages, pictures and images of objects, means for translating said image into a series of electrical impulses; a transmission circuit; and means for retranslating 130

these electrical impulses into a duplicate of the sending image including a series of revolving reflecting surfaces.

4. In an apparatus for electrically transmitting messages, pictures and images of objects, means for translating said image into a series of electrical impulses of varying intensity; a transmission-circuit, and means for retranslating these electrical impulses into a duplicate of the sending image including a series of revolving reflecting surfaces.

5. In an apparatus for electrically transmitting messages, pictures and images of objects, means for translating said image into a series of electrical impulses of varying rapidity; an electrical transmission circuit, and means for retranslating said electrical impulses into a duplicate of the original image including a series of revolving reflecting surfaces.

6. Means for translating lights and shades of an image into electric impulses correlated to each other as the lights and shades of the image are correlated, a transmission circuit, means for translating said impulses into correlated light-rays at the receiving station, and further means for projecting said rays upon a reflecting surface to render the same visible, said reflecting surface including a series of revolving mirrors.

7. Means for translating the optical variations of an image into an undulating current, said undulations correlated to each other as said optical variations are correlated, means for transmitting said undulations, and further means for retranslating said undulations into a duplicate of the optical variations of the sending image, said means including a galvanometer and a series of revolving mirrors.

8. In an apparatus for electrically transmitting graphic messages, pictures and images of objects, a transmitting instrument, including a transparent or translucent message-sheet; a source of light; a motor; a disk; a series of cells in said disk; an element in said cells capable of being electrically excited by rays of light; an electric circuit of which the electrically excitable element forms a part; means for operating said motor; and means for moving the message-sheet between the source of light and the cells, said cells and the means for moving the message-sheet being revolved by said motor at predetermined speed.

9. In an apparatus for electrically transmitting graphic messages, pictures and images of objects, a transmitting instrument, including a suitable message-sheet; a source of light; a motor; a circular disk; a series of cells in said disk; a selenium-element in each of said cells and insulated therefrom; a motor-operating means; means for moving the message-sheet between the source of

light and the selenium-elements; a commutator consisting of a series of sections each of which is connected with one of said selenium elements, and means for rotating the disk with its cells at the same time that the message-sheet is being moved over the source of light.

10. In an apparatus for electrically transmitting graphic messages; pictures, and images of objects, a source of light; a series of revolving cells containing an element which is electrically affected by the rays of light from said source, to increase and decrease the electric conductivity of such element; means for projecting the light-rays from said source of light upon the revolving disk, and its cells, and an electric circuit of which said element is a part.

11. In an apparatus for electrically transmitting messages, pictures, and images of objects, means for projecting said message, picture and image successively and step-by-step upon a revolving disk having a series of cells each of which contains an element which is electrically affected by the light and shade of said message to increase and decrease its electric conductivity in accord with the lighter and darker portions of said image, and an electric circuit of which said element forms a part.

12. In an apparatus for electrical transmission of graphic messages, pictures and images of objects, a transmitting instrument including a transparent or translucent message-strip; a light-secure chamber; a slotted aperture in said chamber, a source of light below, and in line of, said aperture; a series of revolving cells located above said aperture; a motor; means for governing the speed of said motor, an electric circuit of which said revolving cells are a part, and means for moving the message-strip below said slotted aperture and above the source of light.

13. In an apparatus for electrically transmitting messages, pictures and images of objects, a sending instrument, including a light-tight case; a source of light in said case; a reflector surrounding said source of light, there being a slotted aperture in said case through which the rays of light are projected; a transparent or translucent message-sheet containing a picture of the matter to be transmitted; means for moving said message-sheet between said source of light and the slotted aperture; a revolving disk having a series of cells; selenium-elements in said cells and insulated therefrom but electrically connected with said disk; a motor; a source of electrical energy to operate said motor; means for revolving said disk and moving said message-sheet at predetermined speeds; a governor for regulating the speed of said motor, a commutator, the several sections of which are elec-

- trically connected with each of said selenium elements, and an electric circuit of which said disk and its selenium elements are a part.
- 5 14. In a transmitting and receiving apparatus as described, a rotatable disk; a series of cells in said disk; a commutator, the sections of which correspond in number with that of the cells in the disk, and a speed-
10 governor having means for regulating and synchronizing the number of revolutions in the transmitting and receiving instruments.
- 15 15. In a transmitting apparatus as described, a rotatable disk; a series of cells in said disk, a commutator having a series of sections corresponding with the number of cells in said disk and in electrical connection therewith; a motor for revolving said disk; a governor for regulating the speed of
20 said disk; a series of feed-rolls; a suitable message-sheet; and means for moving said message-sheet at a predetermined speed in unison with the revolutions of said disk.
- 25 16. In an apparatus of the kind described, the combination, with a transmitting instrument which translates a picture, and view of objects, into a series of electrical impulses of varying rapidity, and intensity, of a transmission circuit for said impulses; a receiving instrument including a source of light, a galvanometer; means for directing the rays from said source of light upon said galvanometer and means for directing the rays of light from said galvanometer to a
30 reflecting surface consisting of a series of revolving mirrors, whereby the electrical impulses received at the receiving instruments are retranslated into a visible image of the matter sent by the sending apparatus.
- 35 40 17. In an apparatus of the kind described, the combination, with a sending instrument which translates a message which consists of a graphic or visible picture or image into a series of electrical impulses of varying rapidity and intensity, of a transmission circuit for said electrical impulses; a receiving instrument including means for converting these electrical impulses into rays of light
45 of varying intensity; a series of reflecting surfaces; means for projecting these rays of light upon said reflecting surfaces, the angularity of which may be varied to correspond with the variations of the electric current received at the receiving station.
18. In an apparatus of the kind described, the combination, with a transmitting instrument which translates a message consisting of a graphic picture, and a view of objects, into a series of electrical impulses of varying rapidity and intensity, of a transmission circuit for said electrical impulses; a receiving instrument including a galvanometer acted upon by said electrical impulses, a source of light; means for projecting the rays of light from said source of light upon the reflecting mirror of said galvanometer; a reflecting surface consisting of a series of mirrors mounted upon an axle, a motor for revolving said mirror, and means for changing the angularity of said mirrors, whereby the varying electrical impulses acting upon the galvanometer translate these impulses into a visible picture of the message sent by the transmitting instrument.
19. In a receiving instrument for electrical impulses varying in intensity and rapidity, means for translating these varying impulses into rays of light of varying intensity, and an instrument for rendering these rays of light visible, said means including a suitable case; an electric motor in said case; a reflector consisting of a series of mirrors arranged concentrically around the axis of said motor, and means for changing the angularity of said reflecting surfaces, there being an opening in said case through which the visible image of the message sent by the sending instrument may be perceived.
- In testimony that I claim the foregoing as my invention I have hereunto set my hand in the presence of two subscribing witnesses.
- GILBERT SELLERS.
